MARBLE SHOOTER

Peter Donato, Patchogue, N. Y.

Application April 29, 1935, Serial No. 18,945

4 Claims. (Cl. 273—129)

This invention pertains to new and useful improvements in marble shooters of the general type of that constituting the subject matter of my United States Patent No. 1,988,191, issued January 15, 1935.

The primary object of the present invention is to provide, in a manner as hereinafter set forth, a shooter of the character described comprising novel means for releasably securing the marble in position therein, thus permitting the device to be manipulated as desired when in use without danger of the marble dropping therefrom.

Another important object of the invention is to provide, in a manner as hereinafter set forth, novel means for holding the spring actuated plunger in partially retracted position in a manner to retain the marble therein when the device is not in use.

Other objects of the invention are to provide a shooter of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:—

Figure 1 is a view in side elevation of a marble shooter constructed in accordance with the present invention.

Figure 2 is a view in vertical longitudinal section through the invention.

Figure 3 is a side elevational view of the rear end portion of the invention, showing the means by which the plunger is secured in partially retracted position in a manner to retain the marble therein when the device is not in use.

Figure 4 is a view in vertical longitudinal section through the forward end portion of the device, showing the plunger in its forwardmost position.

Figure 5 is a top plan view of the plunger.

Referring now to the drawing in detail, it will be seen that the embodiment of the present invention which has been illustrated comprises a barrel 1 of suitable length and material, said barrel being open at its forward end and closed at its rear end, as at 2. Pressed outwardly in the forward end portion of the barrel 1 is a socket 3, the purpose of which will be presently set forth.

Extending slidably through a slot which is pro-

vided therefor in the end closure 2 of the barrel 1 is a substantially flat stem 4 of suitable metal having fixed on its forward end for reciprocation in the barrel 1 a substantially cup-shaped plunger 5 which is adapted to receive the marble to be projected, as at 6. At its forward end, the plunger 5 terminates in an out-turned flange 7 which is engaged with the barrel 1, the rest of said plunger being spaced from said barrel, as illustrated to advantage in Figure 2 of the drawing. Rearwardly of the flange 7 the plunger 5 has formed therein an opening 8, the purpose of which also will be presently set forth.

The reference numeral 9 designates a resilient finger which is secured on one side of a forward portion of the stem 4, as by a screw 10. The resilient finger 9 extends forwardly between the plunger 5 and the barrel 1 and terminates in an inwardly curved free end portion which is adapted to be projected through the opening 8 in a manner to engage and retain the marble 6 in the plunger 5, as best seen in Figure 2 of the drawing. A coil spring 11 encircles the stem 4 in the barrel 1 and has one end engaged with the closure 2 and its other end engaged with an abutment 12 on said stem 4 for actuating the plunger 5.

The reference numeral 13 designates generally a handle which is provided on the rear end portion of the stem for retracting the plunger 5 against the tension of the coil spring 11. The handle 13 is formed from a single length of suitable metal and includes an eye 14 for the reception of a finger, said handle further including leg portions 15 straddling the stem 14 and pivotally secured thereto, as by a bolt 16. The legs 15 terminate in outturned feet 17 which constitute stops engageable with the closure 2.

In use, with the plunger 5 in its forward position, as shown in Figure 4 of the drawing, the marble 6 is placed therein. The plunger 5 is then retracted against the tension of the coil spring 11 through the medium of the handle 13, as shown in Figure 2 of the drawing. When the plunger 5 is in its forward position, the forward end portion of the resilient retaining finger 9 is engaged in the socket 3, thus permitting insertion of the marble in said plunger. However, it will be noted that when the plunger 5 is retracted, thus disengaging the resilient retaining finger 9 from the socket 3, said finger is projected through the opening 8 in a manner to engage and retain the marble in said plunger 5. When aim has been taken, the handle 13 is released thus permitting the coil spring 11 to drive the plunger 5 forwardly in the barrel 1. As the plunger 5

reaches its forwardmost position and is arrested by engagement of the stops 17 with the closure 2, the resilient finger 9 enters the socket 3 and is thereby withdrawn from said plunger 5, thus releasing and permitting the marble 6 to be projected from the device. When the device is not in use and it is desired to retain the marble 6 therein, the handle 13 is swung to the position shown in Figure 3 of the drawing for retaining 10 said plunger 5 in partially retracted position.

It is believed that the many advantages of a marble shooter constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

20 What is claimed is:—

25 1. A marble shooter comprising a barrel, a stem extending slidably into said barrel, a substantially cup-shaped plunger fixed on the stem and operable in the barrel, said plunger being adapted for the reception of a marble, said plunger having an opening therein, the barrel having a socket therein, a resilient finger mounted on the stem and engageable in the plunger through the opening for retaining the marble in 30 said plunger when said plunger is retracted, said resilient finger being engageable in the socket when the plunger is in its forward position, and means for actuating the plunger.

35 2. A shooter comprising a barrel open at one end, a plunger for the reception of a projectile slidably mounted in said barrel, a resilient finger movable with the plunger and engageable therein for releasably securing the projectile in position, said barrel having a recess therein for the reception of the resilient finger for allowing said finger to disengage from the plunger for releas-

ing the projectile, and means for actuating the plunger.

3. A shooter comprising a barrel open at one end, a stem extending slidably into the barrel through the other end thereof, a substantially cup-shaped plunger, for the reception of a projectile, mounted on the stem and operable in the barrel, said plunger being spaced from the barrel and terminating, at its forward end, in an outwardly flange slidably engaged with said barrel, 10 said plunger having an opening therein, a resilient finger mounted on the stem and engageable in the plunger through the opening for releasably securing the projectile in position in said plunger when said plunger is retracted, the barrel 15 having a socket therein adjacent its open end for the reception of the finger for withdrawing said finger from the plunger for releasing the projectile when said plunger is in its forward position, a spring mounted in the barrel and operatively connected to the stem for yieldingly urging the plunger forwardly, and means mounted on one end of the stem for retracting the plunger against the tension of the spring.

4. A shooter of the class described comprising 25 a barrel open at one end and closed at its other end, a stem extending slidably into the barrel through the closed end thereof, a substantially cup-shaped plunger, for the reception of a projectile, mounted on the stem and operable in the 30 barrel, a resilient finger engageable in the plunger when said plunger is in retracted position, for retaining the projectile therein, a spring mounted in the barrel and operatively connected to the stem for yieldingly urging the plunger forwardly 35 in said barrel, and a handle pivotally mounted on the rear end portion of the stem for retracting the plunger against the tension of the spring, said handle being engageable with the closed end of the barrel for retaining the plunger in re- 40 tracted position.

PETER DONATO.
